UNITED STATES PATENT OFFICE.

ARTHUR L. HALLIDAY, OF NEW YORK, N. Y., ASSIGNOR TO THE BIGELOW CARPET COMPANY, OF WORCESTER, MASSACHUSETTS.

DESIGN FOR A CARPET.

SPECIFICATION forming part of Design No. 14,141, dated July 31, 1883.

Application filed May 16, 1883. Term of patent 3½ years.

To all whom it may concern:

Be it known that I, ARTHUR L. HALLIDAY, of New York, county and State of New York, have invented a new and original Design for 5 Carpets, of which the following is a specification.

The accompanying photograph illustrates my new design for carpets.

This invention relates to a new design for 10 carpets, oil-cloths, and analogous fabrics; and it consists of the new ornamentation of parts herein more fully pointed out.

A represents a branch of flowers with its leaves, the leaves being of the peculiar outline 15 shown, and the flowers being placed on very slender stems. B is another group or branch of flowers and leaves of the peculiar appearance shown. C is a substantially square figure composed entirely of rosettes a, that are arranged in vertical and horizontal lines, as shown. This figure C is placed between the groups A and B, and between two other floral groups, D and E, that are represented in the photograph.

I claim—

1. The design for carpets, consisting of the figure C, substantially as shown. 25
2. The design for carpets, consisting of the figure A, substantially as shown.
3. The design for carpets, consisting of the figure B, substantially as shown. 30
4. The design for carpets, consisting of the figures A B C, substantially as shown.
5. The design for a carpet, substantially as shown.

ARTHUR L. HALLIDAY.
